2,608,268

SUCTION CLEANER

Dale C. Gerber, North Canton, Ohio, assignor to
 The Hoover Company, North Canton, Ohio, a
 corporation of Ohio

Application June 17, 1948, Serial No. 33,627

18 Claims. (Cl. 183—37)

1

The present invention relates to suction cleaners and more particularly to a novel arrangement of parts affording unusual simplicity, compactness and operating efficiency.

It is accordingly an object of the invention to provide a suction cleaner having a unique arrangement of parts. More specifically it is an object to provide a cleaner having a novel filter construction characterized by its simplicity, compactness, high efficiency and cleaning convenience. Another object is to combine a mechanical filter with a final filter in a unique manner.

A further object is to provide a construction in which the final filter also serves to collect dirt separated by the mechanical filter. As a result, the machine may be cleaned and restored to maximum efficiency simply by emptying the dirt from the final filter receptacle.

A further object is the provision of a compact suction cleaner readily separable into two parts one of which houses a quickly detachable filter and dirt receptacle and the other a unitary motor-fan-mechanical filter assembly.

Another object is the provision of a cleaner construction adapted to employ an inexpensive, permeable, disposable paper bag as the final filter and as a dirt receiving receptacle for a separable primary filter whereby the machine may be cleaned by removing the paper bag and replacing it by a fresh one.

Still other objects will become apparent from the detailed description of representative embodiments of the invention and the accompanying drawings in which:

Figure 1 is a vertical sectional view of a preferred embodiment of the invention; and

Figure 2 is a vertical sectional view of an alternative embodiment.

The cleaner comprises a casing 10 having a series of air discharge openings 11. A channel shaped annulus 12 is secured to the upper, inner side of the casing and carries a resilient sealing gasket 13. Dome 14 overlies the casing and is detachably secured thereto in airtight relation by a pair of over-center clamping devices 15. Dome 14 may be provided with a cleaner transporting handle 16.

A combined multiple-stage motor-fan unit and a mechanical or impact filter device generally indicated by numeral 17 is partially housed by dome 14 and is supported therein by means of an annular partition 18. The outer periphery of partition 18 is secured to the dome by screws, rivets or other means. The inner edge 20 is shown as terminating between electric motor 21

2

and the exhaust stage of the multiple-stage fan. The motor flange is secured to partition 18 by screws 22.

Motor shaft 23 projects axially downward through fan casing 24 into casing 10. The upper end of casing 24 is secured to partition 18 by screws as clearly indicated in the drawings. Housed within this casing and secured to motor shaft 23 is first stage 25 and second stage 26 of the suction air fan. Interposed between stages 25 and 26 is interstage 27 one shroud 28 of which projects beyond the periphery and is downturned for convenient support upon fan casing 24 as by screws 29. The interstage directs the air discharged by fan 25 radially inward to the inlet of stage 26 as is customary in multiple-stage fan units. Stages 25 and 26 are held in assembled relation on the motor shaft by means of spool 30 and lock nut 31.

20 The mechanical separator is shown as being of the impact type formed as a frusto-conical stamping 32. The smaller end 33 is unperforated. The larger end flares outwardly to form the radial flange 34 from which a plurality of blades 35 may be stuck. These blades preferably extend at a slight angle to radial lines and function to prevent air from entering between flange 34 and the adjacent portion of housing 24. Thus the blades serve as a substitute for a running air seal at this point.

25 The side walls of separator 32 are slotted and a longitudinal edge of each is struck inwardly as indicated at 36. The slots and associated blades 36 are inclined slightly to the axis of shaft 23 for the purpose of throwing foreign particles of dust and other material outwardly and downwardly into the dirt receptacle.

30 Mounted on the underside of fan casing 24 opposite air inlet 37 to stage 25 is a bearing support 38 for any suitable form of outboard bearing 39 such as as an oilless bearing. Bearing casing 38 is attached to housing 24 in spaced relation by arms 40 so as not to interfere with the free passage of the suction air stream from the interior 35 of separator 32 to the multiple-stage fan. Separator 32 is secured to the shaft by means of spool 41 and lock nut 42. The inner edge of the spool fits against the non-rotating bearing housing.

35 Surrounding base 26 of the fan is an annular sheet metal stamping 44. Stage 26 discharges into the chamber thus formed through a plurality of ports 45 in casing 24. A conduit 46 at one side of chamber 44 conducts the discharge air into annular final filter chamber 47 formed by

the imperforate cylindrical member 48 and the wall of filter bag 49.

Filter bag 49 may be of any suitable filter material but preferably is of paper construction in order that it may be disposed of when full and replaced by an inexpensive new one. The outer portion of its closed bottom 50 is held pressed against a resilient support such as a sponge rubber pad 52 in the bottom of dirt receptacle 10 by means of beaded flange 53 on the bottom of cylinder 48. This cylinder is preferably attached to diaphragm 18 so as to be removable along with the cleaner end cap 14. The upper end of the filter bag has an outturned flange 54 which seats on the inner rim of annulus 12. One or more gaskets of suitable material may be placed above or below flange 54 to allow for manufacturing tolerances and to assure an airtight seal.

From the foregoing it will be clear that my dirt receptacle is provided with an inner main filter chamber 55 which serves to collect the major portion of the dirt separated out by the impact separator 32. Surrounding this is an annular final filter chamber 47. The dirt collected in chambers 55 and 47 is all contained within the filter bag 49 and is intermingled when separating partition 48 is removed along with the motor fan and housing 14.

Air passing through the filter flows into the annular space 56 formed by the filter and casing 10, and is discharged into the room through openings 11 in casing 10.

Cleaning tools and the usual flexible hose are connected to the tubular inlet coupling 58 mounted in the side wall of casing 14. This coupling 35 communicates at its inner end with the upper end of cylinder 48.

Operation

The operation of the preferred form of this novel cleaning apparatus will be self-apparent from the foregoing description but will be reviewed briefly here. After connecting the conventional cleaning tools and flexible hose to coupling 58, the operator presses an electrical switch for the motor fan unit to start it in operation. This switch, not shown, may be of the press-press type mounted in the top of casing 14 and operated by foot pressure. The fan unit sucks the dirt-laden air through the nozzle, the hose connections and into the top of chamber 55. The air then passes through slots 36 in the impact separator and through inlet opening 37 into the eye of stage 25. Thereafter, the air flows through the interstage 27 into the inlet of stage 26. The air discharging from this stage passes through openings 45 into the annular chamber 44 and through its discharge outlet 46 into the final filter chamber 47. This clean air then passes through the wall of filter 49 into chamber 56 and through openings 11 in casing 10 back into the room. The bulk of the dirt carried by the air is separated by the impact separator 32 and collects in chamber 55. The smaller particles of dirt still carried by the air stream then pass into chamber 47 of the final filter where they are easily and efficiently removed by the relatively clean wall of filter 49.

It will be noted that the great bulk of the dirt is removed in chamber 55 and is prevented from coming in contact with the filter wall by reason of partition 48. Instead, it collects on the bottom of the filter bag. The small amount of fine dust not separated by impactor 32 is removed by the vertically disposed wall 49 of the filter from which it readily falls into the bottom of dirt-

collecting space 47. By picking up the cleaner and setting it on the floor two or three times rather sharply, the small amount of dirt tending to adhere to the filter wall will be easily dislodged and will collect at the bottom of chamber 47.

It will therefore be apparent that the filter in this novel arrangement and construction of parts is so located and positioned as to maintain a very high operating efficiency at all times even after the collection chambers have become substantially filled with dirt.

To remove the collected dirt the operator simply releases clamps 15 and lifts cap 14 with its attached motor fan unit and separator cylinder 48 from casing 10. The dirt in chambers 47 and 55 then commingles in the filter bag. The dirt is simply and expeditiously removed by the operator grasping the top of the filter bag and collapsing it in airtight manner against the collected dirt as the bag is removed to a point of disposal. A fresh paper filter is then inserted and the cap reassembled and clamped in position.

The principles of this invention can be carried out very effectively when the parts are arranged other than vertically as just described in connection with the preferred form. For this instance, one alternative arrangement is illustrated in Figure 2 wherein the similar or corresponding parts to those in the preferred form are designated by primed reference numerals. In view of the substantial identity of the greater number of parts, it is not thought necessary to make a detailed description of each, reference being had to the description of the preferred form for a detailed understanding of the modification shown in Figure 2.

In general it will be noted that the construction is very similar except that the parts are arranged horizontally rather than vertically. The dirt separation and storage casing 10' mates with a removable end cap section 14' which, as in the preferred form, carries the motor fan unit as an integral assembly. Casings 10' and 14' may be separably connected together by over-center snap acting clamps or by any equivalent arrangement. The assembled unit may be mounted on wheels or, as illustrated herein, upon skids 65-65.

It will be noted that the air intake coupling 58' differs from that in the preferred form in that it extends outwardly from the casing and is bent to lie parallel to but spaced from housing 14'. This latter portion, designated as 66, is secured to the casing near its outer end by a bracket 67 and serves as a convenient carrying handle for transporting the cleaner from place to place about the house. End cap 14' may also be provided with a stamping 68 having struck inwardly therefrom a rounded handle forming portion 69. This handle corresponds to handle 16 of Figure 1 and facilitates carrying of the cleaner in a vertical position.

It will also be noted that the end of casing 10' is flat making it possible to store the cleaner in upended position wherein it occupies a minimum of storage space. Handle 69 makes it convenient to place the cleaner in vertical storage position and to carry it to and from a place of use.

In lieu of air discharge openings 11 in the side wall of the casing, member 12' and the rim of diaphragm 18' are provided with aligned openings 70. A single opening 71 is located in the end of cap 14'. As illustrated, this opening is provided with a hose coupling for the connection of

the customary hose and tools should it be desired to use the discharged air stream for such purposes as hair drying, paint spraying, dispersal of deodorants and the like.

Operation

The modification operates in the same manner described above in connection with the preferred form. Dusting tools and the usual hose are connected to inlet coupling 58'. Operation of the motor-fan unit draws air in through this coupling, tubular handle 66 and one end of the main dirt chamber 55'. The air then passes into impact separator 32' and through inlet 37' to the first stage 25' of the fan. The air then passes through interstage 21' and into the second stage 26'. The air next passes into the chamber formed by annulus 44', through discharge tube 46' and into the final filter chamber 47'. Any dust remaining in the air is removed as the air passes through the disposable paper filter 49'. The clean air next passes through openings 70 and is exhausted into the room through opening 71 and coupling member 72.

To dispose of the dirt and insert a new filter, the cleaner is suspended onto its bottom after which the clamps (not shown) are loosened and the entire top portion of the unit, including the motor fan unit, is withdrawn vertically. Filter bag 49' may then be lifted from the cleaner together with all the dirt collected in the main chamber 55' and in final filter chamber 47'. The top of the bag may then be closed and the bag and its collected dirt disposed of. Thereafter a new bag is inserted and end cap 14' is replaced and clamped to the bottom section. This simple operation is all that is required to restore the cleaner to maximum cleaning effectiveness.

It will now be apparent that the present invention embodies an unusually unique arrangement of parts for a suction cleaner. Not only is the construction extremely simple and rugged, but it incorporates a novel filter arrangement in which the bulk of the dirt is stored entirely out of contact with the filtering surface. Moreover, the filtering bag wall is reserved for use as a final filtering surface. Upon disassembly, the dirt separated by both the primary and the final filters is automatically collected in the disposable filter bag which can be simply removed, thrown away and replaced by a fresh bag.

Obviously the various parts can be otherwise formed and disposed relative to one another without departing from the essential principles of the present invention. It is also to be understood that although the mechanical filter illustrated is of the impact type, other types may be used. For example it can be replaced by various arrangements of cyclone filters. Thus, the incoming dirty air stream may expand downwardly into chamber 55' as the dirt settles out. A centrally located conduit can then be used to conduct the air stream to inlet 37' of the fan unit, all as is well known in the cyclone filter art.

It will therefore be understood that the protection for which application is made is not confined to the particular combination of features or elements set out in the annexed claims. Protection is herein applied for for any one or more of the features or elements referred to in the following claims, or described in the foregoing specification, or shown in the accompanying drawings, either independently or in combination.

What is claimed is:

1. A suction cleaner comprising a two-part cas-

ing, a motor-fan unit mounted within one of said parts, a removable filter bag having an integral bottom mounted within the other of said casing parts, a partition cooperating with the bottom of

5 said filter bag to divide said filter into a main dirt collecting chamber and a supplemental dirt collecting chamber, means for directing dirt-laden air through first one and then the other of said chambers, and means in said main dirt chamber to separate major portions of the dirt from said air stream as it passes therethrough and to deposit the separated dirt in said bag.

10 2. A dirt separator for use in separating dirt from an air stream comprising a casing, a removable filter bag having a closed end supported therein, resilient means mounted opposite the closed end of said bag, an imperforate member within said bag and supported against said closed bag end, opposite said resilient means to divide the bag into two chambers, and means for directing a dirt-laden air stream through first one and then the other of said chambers.

15 3. A dirt separator as claimed in claim 2 in which said partition is shaped to form a central main dirt separation chamber and a surrounding supplemental dirt separation chamber.

20 4. A dirt separator as claimed in claim 2 in which said imperforate member is shaped to form a central main dirt separation chamber and a surrounding final filter chamber, and mechanical filter means associated with said main dirt chamber through which said air stream passes operable to separate a major portion of the dirt therefrom.

25 5. A suction cleaner comprising two open ended casings adapted to inter-fit to form a housing, a motor-fan unit mounted within one of said casings and removable therewith, a filter bag mounted within and having an open end positioned across the opening of said other casing, a tubular member extending lengthwise of said bag and cooperating with the bottom thereof to form a central main dirt chamber and an outer final filter chamber, and means associated with said motor-fan unit for directing a dirt-laden air stream through said central main dirt chamber and then through said final filter chamber.

30 6. A suction cleaner as claimed in claim 5 in which said main dirt chamber is provided with a mechanical filter in the path of said air stream.

35 7. A suction cleaner as claimed in claim 5 having a power-driven mechanical separator operable to separate dirt from said air stream as it passes through said main dirt chamber.

40 8. A suction cleaner comprising two cup-shaped casings having their rims adapted to interlock to form a housing, a motor-fan unit mounted within one of said casings, a filter bag within said other casing adapted to be closed when said casings are assembled, an imperforate member removable with the casing carrying said motor-fan unit, said member cooperating with the closed end of said filter to divide the filter into a primary dirt chamber and an outer final filter chamber, an impact dirt separator driven by said motor-fan unit and located to direct dirt separated thereby into said primary chamber, and means associated with said motor-fan unit to direct an air stream through said impact dirt separator and then through said final filter chamber.

45 9. A suction cleaner as claimed in claim 8 in which resilient means is interposed between one of said casings and the bottom of said filter bag

opposite said imperforate wall to form a seal between said primary and final filter chambers.

10. A suction cleaner comprising two open ended casings adapted to inter-fit to form a suction cleaner housing, a motor-fan unit mounted within one of said casings, a tubular filter member having one end removably supported across the other of said casings near the open end thereof, the other end of said tubular filter having an in-turned flange located adjacent the bottom of said other casing, an imperforate tubular member of smaller cross-section than said filter extending lengthwise within said filter and adapted to seat on said in-turned flange to hold said filter assembled in said casing, said imperforate member cooperating with said filter to form a central dirt chamber and an outer annular dirt chamber, and means associated with said motor-fan unit for directing a dirt laden air stream through first one and then the other of said dirt chambers.

11. A suction cleaner having a cup-shaped casing, an in-turned flange near the peripheral lip of said casing for supporting a filter bag, a filter bag having an open end adapted to be mounted and seated upon said in-turned flange, the other end of said filter bag being positioned adjacent the bottom of said casing, a readily removable imperforate tubular member of smaller cross section than said filter adapted to be supported within said filter bag and cooperating therewith to form a central dirt collecting chamber and an annular dirt collecting chamber, means for supporting a motor driven suction fan on said casing, the inlet of said fan being in communication with said central dirt collecting chamber and the discharge end thereof being in communication with said annular dirt collecting chamber, and duct means for conducting a dirt-laden air stream into said central dirt chamber.

12. A suction cleaner comprising a two part casing readily separable from one another for removal of a dirt filtering bag, a motor fan unit secured to and housed in one of said casing parts, a unitary filter bag having an open end and a closed end, means removably supporting said filter bag within said casing, imperforate means extending through the open end of said bag and cooperating with the closed end thereof to divide said filter bag into a first dirt separation chamber and a second dirt separation chamber, the arrangement of said filter and imperforate means being such that dirt separated in both said first and second chambers collects in said filter bag and is removable therein when the same is withdrawn from said cleaner, and means associated with said motor fan unit for directing dirt laden air through first one and then the other of said dirt separation chambers.

13. A suction cleaner comprising a two part casing readily separable from one another for the removal of a dirt filtering bag, a motor fan unit secured to and housed by one of said parts, a unitary filter bag having an open end and closed end, means removably supporting said filter bag within the other of said parts and leaving said filter bag free for removal therefrom when said casing parts are separated, imperforate means cooperating with said closed end to divide said filter bag into a first dirt separation and collecting chamber and a second dirt separation and collecting chamber, and means associated

with said motor fan unit for directing dirt laden air through said first dirt separation and collecting chamber and then through said second dirt separation and collecting chamber.

14. Separator means for use in separating dust from air comprising a housing, a readily removable, unitary one-piece air permeable receptacle therein, a non-permeable partition within said receptacle and cooperating therewith to form a main dirt chamber and a supplemental dirt chamber, means for separating dirt from an air stream as it passes through said main dirt chamber and depositing the separated dirt into said air permeable receptacle, and means directing the partially de-nuded air stream into said supplemental dirt chamber and through said permeable receptacle to remove additional dirt from said air stream whereby all the separated dirt collects in either said main or supplemental dirt chambers of said air permeable receptacle and is removable therein from said housing.

15. A separator as defined in claim 14 in which said non-permeable partition is readily removable from said receptacle whereby the separated dirt in both said main and supplemental chambers co-mingles and is contained entirely within said air permeable receptacle for ready removal from said separator.

16. A dirt separator for a suction cleaner having a casing, a unitary dirt filter bag having a closed end and an open inlet end, means for detachably seating the open end of said bag in said casing, readily removable cover means normally holding said bag in place on said seating means and, upon removal, leaving said bag free for withdrawal from said casing, a tubular imperforate member separably supported within said bag with one end thereof bearing against a wall of said bag and having a major portion of its walls spaced from the walls of said bag to form a first dirt collecting chamber interiorly of said tubular member and a second dirt collecting chamber between the exterior thereof and the adjacent walls of said filter bag, and means for directing a dirt laden air stream into the central part of said tubular means and thereafter into the annular space between the exterior surface of said member and said filter bag.

17. A dirt separator for a suction cleaner as defined in claim 16 in which said removable cover, said air directing means and said tubular member are removable from said casing leaving the dirt separated in said central chamber and in said annular space collected in said removable filter bag.

18. A dirt separator for a suction cleaner as defined in claim 17 in which said air directing means and said tubular member are removable from said filter bag as a unitary assembly.

DALE C. GERBER.
